(No Model.)

J. HORNIG.

MECHANISM FOR CONVERTING ROTARY INTO OSCILLATING MOTION.

No. 252,768.

Patented Jan. 24, 1882.

UNITED STATES PATENT OFFICE.

JULIUS HORNIG, OF JERSEY CITY, NEW JERSEY.

MECHANISM FOR CONVERTING ROTARY INTO OSCILLATING MOTION.

SPECIFICATION forming part of Letters Patent No. 252,768, dated January 24, 1882.

Application filed August 5, 1881. (No model.)

To all whom it may concern:

Be it known that I, JULIUS HORNIG, of Jersey City, in the county of Hudson and State of New Jersey, have invented a new and useful Improvement in Mechanisms for Converting 5 Rotary into Oscillating Motion, of which the following is a full, clear, and exact specification.

Figure 1 is a side elevation of the original 10 machine. Fig. 2 is a side elevation of my improvement. Fig. 3 is a plan view of the same. Fig. 4 is the same view as Fig. 3, but showing a different arrangement of the eccentric-strap. Fig. 5 is a perspective view of a modification 15 of the improvement. Fig. 6 is a sectional plan view of the same.

Similar letters of reference indicate corresponding parts.

The object of this invention is to improve the 20 construction of the mechanism for converting rotary into oscillating motion for which Letters Patent No. 46,237 were granted to me February 7, 1865, and Reissued Letters Patent No. 3,717 were granted to me November 9, 1869, 25 in such a manner as to facilitate and cheapen the repairing of the said mechanism should it be broken by being overtaxed.

The invention consists in the combination, 30 with the rotating eccentric and the oscillating lever, of the roller or segment and the break-pin, whereby the breaking of the said lever will be prevented should its movement be obstructed; and, also, in the combination, with the eccentric-strap and the break-pin, of the arm 35 having a slot or clearance-space to receive the said pin, whereby the said arm will be kept from being broken should the oscillating lever be obstructed, as will be hereinafter fully described.

40 I will describe the improvement as applied to a shear, but do not limit myself to that use, as it can be applied with equal advantage to various other mechanisms.

A represents the frame of the machine, in 45 bearings in the upper part of which revolves the shaft B. The shaft B is connected by gear-wheels C D with the driving-shaft E, which revolves in bearings in the lower part of the frame A, and to which motion is given from a 50 steam-engine or other suitable power.

To the shaft B is attached an eccentric or

cam wheel, F, by which motion is given to the oscillating lever G. The lever G is pivoted to the lower part of the frame A, and in the drawings is represented as having a shear-blade, 55 H, attached to it, but which can be connected with any suitable machinery that is required to be operated by an oscillating movement. In the original mechanism the lever G rested directly against the eccentric F, so that if the 60 machine was overtaxed the lever G had to break and be replaced by a new one. In my improvement the upper end of the lever G is so constructed as to leave a clearance-space between the said lever and eccentric, so that 65 the eccentric can revolve without touching the lever. In this case the face of the eccentric F rests against the face of a roller, I, or segment I', connected with the upper end of the lever G. The upper end of the lever G is slotted to 70 receive the hub of the roller I or the web of the segment I'. In case a roller I be used, it revolves upon a pin, J, attached to the lever G. In case a segment I' be used, it is supported by the pin J, and is held from revolving by a 75 small second pin, K, passing through it and through the said lever, as shown in Fig. 5.

The pin J is made of such a size and strength as to be the weakest point of the mechanism, so that should the mechanism be taxed beyond 80 its capacity the said pin will break, and thus prevent the lever G from being broken.

Additional security can be had by making the shell of the roller I or segment I' sufficiently light to be crushed should the lever G 85 be obstructed. With this construction the lever G is pushed forward to make its stroke by the pressure of the eccentric F, against the roller I or segment I', and is drawn back, after making its stroke, by the eccentric-strap L, 90 which passes around the eccentric F and has a lug or arm, M, formed upon or attached to it. The arm M is connected with the pin J by a loop-clevis or U-shaped bar, N, which passes around the said pin, and is secured to the arm 95 M by a pin or bolt, so as to leave a slot or clearance-space, O, between the end of the arm M and the pin J, to allow the said arm to move forward without being broken should the forward movement of the lever G be obstructed. 100

If desired, the arm M and loop N can be made in one piece and slotted to receive the pin J.

Having thus fully described my invention, I claim as new and desire to secure by Letters Patent—

1. In a mechanism for converting rotary into oscillating motion, the combination, with the rotating eccentric F and the oscillating lever G, of the roller I or segment I' and the break-pin J, substantially as herein shown and described, whereby the breaking of the said lever will be prevented should its movement be obstructed, as set forth.
2. In a mechanism for converting rotary into

oscillating motion, the combination, with the eccentric-strap L and the break-pin J, of the arm M N, having a slot or clearance-space, O, substantially as herein shown and described; whereby the said arm will be kept from being broken should the oscillating lever be obstructed, as set forth.

JULIUS HORNIG.
